UNITED STATES PATENT OFFICE.

LOUIS E. RICHMOND, OF CLEVELAND, OHIO, ASSIGNOR, BY MESNE ASSIGNMENTS, TO THE AUTOCALL COMPANY, OF SHELBY, OHIO, A CORPORATION OF OHIO.

ELECTRIC BELL.

Original application filed May 8, 1919, Serial No. 295,688. Divided and this application filed July 24, 1920. Serial No. 398,644.

This invention relates to electric bells, such as are used for signal and alarm systems.

One object of the invention is to provide an improved electric bell having an exposed gong and provided with operating mechanism which is enclosed within a sealed casing so as to be proof against water, moisture, gases, fumes, and the like. A further object of the invention is to provide a bell of this kind adapted to receive gongs of varying sizes and consequently of more or less powerful and penetrating sound, and which bell is also adapted for direct connection to a wall or other support for open wiring, or to an outlet or junction box for conduit wiring.

A further object of the invention is to provide a waterproof bell which is suitable for use either as a vibrating or as a single stroke bell, and either with direct or alternating current, and which is efficient as regards the magnetic field and effects when used with alternating current. A further object of the invention is to provide an electric bell whose working parts are supported by a frame of simple construction capable of being assembled without soldering, riveting, welding, or other expensive operations. Further objects of the invention are in part obvious and in part will appear more in detail hereinafter.

In the drawings, Fig. 1 represents a central sectional elevation through one form of bell embodying the invention, and showing the same attached to a junction box; Fig. 2 is a similar section through another form of bell base; Fig. 3 is a front elevation of the bell; Fig. 4 is a detail elevation illustrating a portion of the bell base shown in Fig. 2; Fig. 5 is a rear elevation of the bell with the junction box and other parts omitted to expose interior parts; Fig. 6 is a front elevation of the junction box shown in Fig. 1; Fig. 7 is a detail rear elevation illustrating the vibrating contacts; Fig. 8 is a detail sectional view on the line 8—8, Fig. 1; Fig. 9 is a detail side elevation illustrating the means for securing together the bell casing and junction box or bell base; Fig. 10 is a detail view of the armature arm and contacts thereon; Fig. 11 is a detail sectional view on the line 11—11, Fig. 1, looking in the direction of the arrows; Fig. 12 is a de-

tail perspective view of the magnet frame; Fig. 13 is a similar view illustrating the parts of said frame prior to assembly thereon; and Fig. 14 is a sectional view of the compression contact.

The bell illustrated in the drawing comprises a hollow casing or frame 1 having an inner chamber 2, and which may be of any suitable shape but which is shown as of generally circular form in front elevation, as shown in Fig. 3. The front of said casing is closed by a wall 3 having a vertically extending centrally disposed thickened portion or rib 4. The annular wall or flange 5 of the casing, at its rear edge, is formed to fit either a shallow base or closing plate 6 for open wiring, or the wall of a conduit or outlet box 7, as may be desired. Those parts which are to be secured directly to the wall or other support, such as the base 6 and box 7, are provided on their rear faces with several shallow spacing pads 8 and near their upper portions with perforated ears 9 to receive bolts for securing them to the support. On either side said base 6 and box 7 are also provided with screws 10 pivoted thereto on pins 11, said screws having nuts 12 held permanently thereon by suitably deforming the outer ends of the screws. When the bell casing is pushed into place on its seat on the base 6 or box 7, as the case may be, said screws are swung into position between the ears 13 on the bell casing and the nuts 12 are screwed up to securely fasten the parts. This connection is easily made and enables the bell mechanism to be readily removed from its supporting part, when desired. In installing a signal system the full wiring system can be first laid in place with all junction boxes or wall bases closed by blank plates, as is usual, and the bells can be later installed as desired or when needed by merely removing the blank plates and putting the bells in place.

Base 6 near its bottom and on its inner face is preferably provided with a rib or raised portion 14, forming a pocket or recess 15 adjacent to the openings 16 for the lead wires. Conduit box 7 may be provided with one or more openings for lead wires closed by ordinary knock-outs 17 or threaded to receive conduit, as indicated at 18, as desired. Indeed, any arrangement is suitable in which the connection of the conduit to the

junction box may be made water-tight. 18^a represents a sealing gasket.

To the front wall of the casing is secured the gong 19. Said gong is preferably protected against blows from above and against water or other liquids dropping or depositing thereon by an apron member 20 secured by the screws 21 to the bell casing. The gong is supported by the bell casing, such as by being mounted upon a hollow post 22 to which it is secured by a bolt 23 threaded into an opening 24 in the rib 4. The apron 20 may have a tongue portion 25 depending in front of the rib 4, so that the bolt 23 can be passed through the opening in said apron and then into the bell casing. The apron thereby serves as an additional gong support.

Gongs of various sizes may be readily secured to the same bell casing, the only essential requirement being that the upper rim portion of the gong which is to be struck by the hammer or clapper should always lie at the same point, regardless of the size of the gong. Various sizes of gongs may be attached by locating several threaded openings 24 for receiving the bolt 23, and the corresponding openings in the tongue 25, at different elevations along the rib 4, or, different sizes of aprons may be used for the different gongs.

The upper portion of the box or casing is provided with an inner cross wall 26 and two parallel vertically extending inner side walls 27 forming a narrow outer chamber 28 opening out through a vertical slot 29 in the front casing wall. A vertical portion of the wall 26 serves as a seat to receive and support a bearing for the shaft of the striking hammer or clapper 30. Said bearing comprises two hollow members 31, 32 provided respectively with an interlocking rib and groove, as shown at 33, and held together and to the wall 26 by bolts 34. Mounted to rotate in an opening between said bearing members is a short shaft 35 provided with a non-circular reduced portion 36 to which is secured the shank of the clapper or hammer. Said shank is slotted longitudinally at its end and is slipped laterally into place on the shaft, after which it is secured in place by peening over the ends of the shank or soldering or welding it in place, as desired. On either side of said shank the shaft 35 and bearing members are provided with interlocking collars and grooves 37 forming a tortuous passage way to prevent entrance of moisture into the chamber 2, the joints being further sealed if desired by felt washers 37^a.

The clapper or hammer on its outer end is provided with a striking head 38 formed by perforating an enlarged circular portion of the shank and securing thereto by a rivet 39 one or more washers 40, as may be desired. This construction enables the weight

of the hammer to be adjusted by using the proper number and weight of washers for any particular size of gong or strength of bell stroke desired.

Shaft 35 has secured thereto a bail 41, 70 which may be made of strong wire or rod and which is in general of U-form, the arms of said bail being passed through and secured in openings in the ends of the shaft. This bail forms an operating connection 75 from the mechanism in cavity 2 to the hammer or clapper 30.

Within the cavity 2 is located an electromagnet so arranged as to be capable of actuating the bell hammer when energized by 80 current passing through its coil. Said electromagnet is preferably so constructed and its coil is so wound as to be capable of operation upon either alternating current circuits of relatively high voltage or upon direct current circuits. As illustrated, the electromagnet comprises a coil 42 wound about one of the legs or poles 43 of a magnet core whose other leg is indicated at 44. The magnet core shown is of U-form, its legs 43 90 and 44 and base 45 being integral with each other and being made up in laminated form as shown in Fig. 11 to reduce eddy current effects and enable the coil to lie indefinitely on closed circuit without undue heating. 95

The laminations of the core are held together and to the bell casing or box by a supporting frame 46. Said supporting frame comprises two like side members provided with ears 47 through which screws 47^a 100 are passed into the bell casing, while the laminations of the core are secured between the side members of the frame by rivets 48.

The side members of the magnet frame are held together by a cross bar or member 49, 105 the joint between said frame member and said cross bar being of peculiar form. As indicated in Figs. 12 and 13 each side frame member near the outer end of its leg is provided with corner notches 50 and between 110 the same and at a lower level with an opening 51. The cross bar 49 is blanked out so as to provide at each end a pair of short tongues 52 extending beyond the shoulder 53, and between said tongues with a longer 115 tongue 54 whose outer end is depressed below the body of the bar. The two frame parts are assembled by passing the tongues 54 of a cross bar through the openings 51 in the frame parts and with tongues 52 entering the notches 50 until the shoulders 53 abut the side frame parts. While holding the parts in this position the ends of the longer tongues 54 are bent over as shown at 120 55, Fig. 12, thereby firmly and solidly uniting the parts, but permitting a slight amount of yield so that the frame readily accommodates itself to the laminations which it is to hold.

The projecting legs of the side frame parts 130

serve as supports for an armature arm, for which purpose they are provided with elongated openings 56. The armature arm comprises a metal strap 57 bent into U-form and having an armature portion 58 formed by securing between the arms of said U a series of laminations. At the lower end of said armature is a cross pin 59 whose opposite ends extend through the elongated openings 56. The upper end of the U-frame of the armature arm indicated at 60 lies opposite and behind the bail 41 of the bell clapper.

As will be observed the legs or poles of the magnet core lie perpendicular to the front wall or base of the bell casing, while the neutral portion 45 of the core lies parallel thereto. The magnet core is therefore located in an efficient position as regards concentration of the magnetic flux, so that leakage of magnetism to surrounding masses of metal is reduced or minimized. At each energization of the electromagnet by passing current through its coil the armature 58 is attracted and swings to the left in Fig. 1 from the dotted line to the full line position, the upper end of said armature arm cooperating with the clapper bail to throw the clapper upwardly and engage the gong. Pin 59 has loose sliding motion horizontally in the elongated slots 56, so that the lower end of the armature invariably settles with full contact against the lower pole or leg of the core. When the core is de-energized, however, the armature swings away from the core, due to the weight of the clapper, and the pin 59 moves in the slots 56.

Preferably the armature is so arranged that in its final position on energization it contacts directly with the upper magnet pole, so as to produce a practically completely closed magnetic field. Also, the contacts on the armature at the upper magnet pole are of special form designed to withstand the heavy blows encountered in the extremely heavy service to which the bell is subject and to prevent freezing or sticking of the armature to the magnet core by the effects of the residual magnetism. In the present instance the contacts comprise one or more small masses of suitable non-magnetic metal, such as a phosphor bronze composition, as indicated at 60^a, firmly secured to the laminations of the armature in intimate electrical contact therewith. The attachment is preferably made by a welding operation, such as by holding small pieces of phosphor bronze metal against the laminations of the armature and welding the same thereto by an acetylene or oxy-hydrogen flame, after which the contacts are ground or filed off to a flat contacting surface. On its backward movement the armature arm swings to the right in Fig. 1, while the clapper or hammer drops. To deaden the sound the casing wall may be provided

with a cavity to receive a felt cushion 61 against which the hammer seats in its retracted position.

The bell may also be provided with means for limiting outward movement of the armature away from its coil, to prevent said armature from moving to a position beyond the effective pull of the coil. This result may be accomplished by securing beneath the screws 34 a metal strip 62 whose lower end serves as a stop or abutment for the armature member 57. The outward swing of the armature arm can be readily adjusted by bending this metal strip inwardly or outwardly, as shown by the dotted lines Fig. 1.

The electrical connections to the coil are preferably so arranged that the wiring to the shallow base 6 or junction box 7 can be first completed and the electrical connection to the coil is thereafter made by merely attaching the bell casing with the mechanism therein directly to the base or junction box. For this purpose the bell casing is provided at suitable places in its cavity 2, for example one on either side of the magnet frame, with compression contacts 65, from each of which contacts a wire leads to the magnet coil, said contacts being mounted on brackets 69. One of said contacts is shown in detail in Fig. 14. It comprises a tubular base 66 of insulating material in which is located a plunger 67 pressed outwardly by a spring 68. Said spring seats against a conducting base 70 connected by the lead wire 71 to the coil. Plunger 67 normally extends slightly beyond the edge of the wall of flange 5. Similar compression contacts 72 are located within the conduit box 7 or shallow base 6, as the case may be, and in such position as to register with those in the bell casing when the casing is applied to the base. Therefore, mere attachment of the bell casing to the base or conduit box completes the electrical circuits. The contacts in the shallow base may be simple resilient spring strips, as shown at 72^a, Fig. 2.

When a shallow base is used the lead wires running to the compression contacts therein are passed through the openings 16, after which the cavity 15 in said base is filled with wax or similar easily melted insulating material, as at 73, Fig. 2, which not only secures the lead wires in place but also seals the openings 16 against the entrance of moisture.

When the circuit connections pass directly through the coil the bell is what is known as a single stroke bell and produces a single stroke of the gong each time the circuit is completed, the hammer dropping back when the circuit is broken. Under some circumstances vibrating action, or in other words, rapidly repeated bell strokes are desirable. For this purpose the bell mechanism may be

provided with contact mechanism in the bell circuit actuated by movement of the armature arm, so as to rapidly make and break the circuit. As illustrated the frame bridge member 49 may serve to support an insulating block 75 secured thereto by screws 76^a. In a recess of said block is secured a spring metal strip 76 having a contact 77 co-operating with a contact 78 on an insulating block 79 carried by the armature arm. The contacts 77, 78 are included in the circuit to the coil by running one of the wires from the compression contact 65 to the strip 76 and from the contact 78 to the coil. Spring arm 76 is bent so that by its own resiliency it has a tendency to follow the armature arm in its movement. Indeed, were the armature arm moved slowly to the left in Fig. 1 contacts 77, 78 would not separate. However, when the coil is energized the armature arm moves to the left very rapidly and at a speed faster than the spring arm 76. Therefore, the circuit is quickly broken. The rebound of the hammer from the vibrating gong throws the armature arm back again so that the armature contact 78 meets the approaching spring contact 77 thereby again completing the circuit and producing another action. This arrangement is found to produce very rapid vibrating action without chatter. Spring contact arm 76 may be reinforced to increase its resiliency by a supplemental backing spring 80, although this is not essential.

This application is a division of my prior application for electric bells, filed May 8, 1919, Serial No. 295,688.

What I claim is:

1. An electric bell, comprising a hollow casing having a vertical front wall and a rearwardly extending peripheral wall forming a chamber, an electro-magnet within said chamber secured to the front wall with its core extending rearwardly therefrom, an

armature member swinging in a vertical plane, the upper portion of said front wall receding to form an outer recess, a striker, means for actuating said striker, said striker projecting forwardly in said recess from the receding portion of said front wall. 45 50

2. An electric bell, comprising a hollow casing having a vertical front wall and a rearwardly extending peripheral wall forming a chamber, an electro-magnet within said chamber secured to the front wall with its core extending rearwardly therefrom, an armature member swinging in a vertical plane, the upper portion of said front wall receding to form an outer recess, a horizontal packed shaft mounted on the receding portion of said front wall and carrying a striker extending forwardly in said recess, and bail operating means carried by said shaft within said chamber for actuation by said armature member. 55 60 65

3. An electric bell, comprising a hollow casing having a vertical front wall, a striker in front of said wall, electro-magnetic means within said casing for operating said striker, a gong protecting apron shield on the casing, 70 and cooperating means spaced on said shield and wall for securing gongs of various sizes to said wall beneath said shield each with a portion thereof properly related to the striker. 75

4. An electric bell, comprising a hollow casing having a vertical front wall, a striker in front of said wall, electro-magnetic means within said casing for operating said striker, a gong protecting shield carried by the casing and having a portion depending in front of the front wall thereof, the casing and shield being provided with a plurality of spaced opposed openings to receive securing means for gongs of various sizes. 80 85

In testimony whereof I hereby affix my signature.

LOUIS E. RICHMOND.
